Inventor
Frank Miller:
By *R. S. Bush* Atty.

UNITED STATES PATENT OFFICE.

FRANK MILLER, OF LOS ANGELES, CALIFORNIA.

PISTON-RING MOUNTING AND REMOVING TOOL.

Application filed January 24, 1927. Serial No. 163,096.

This invention relates to improvements in piston ring mounting and removing tools.

Among the objects of my invention is to provide a tool, of simple, durable and inexpensive construction, in which ring spreading means are combined with ring holding means so that a ring may be spread to a diametrical dimension greater than the piston diameter and so held and moved relative to the piston for either mounting or removing the ring in or from a ring-groove of the piston.

A further object is to provide a tool of the recited character with adjustable parts whereby it may be adapted to rings of varying diametrical and sectional dimensions.

A further object is to provide a tool, as characterized, with adjustable expansion limiting means in order to avoid possibility of ring breakage.

A further object is to provide a tool as characterized, whose ring spreading means are wholly and continuously visible during both ring removing and ring mounting operations.

A further object is to provide a tool for spreading piston rings whose ring-end engaging parts are designed to function regardless of the shaping of the ring-ends.

And a still further object is to construct all of the several parts of the tool as die-stampings or screw-machine products and complementary or inter-changeable to the end that cost production is minimized and the tool made ready repairably, as by replacement of parts.

My improvements consist in the novel construction, arrangement and combination of parts as hereinafter fully, clearly and concisely described, definitely pointed out in my claims and illustrated by the accompanying drawings (2 sheets) in which—

Fig. 1, is a view of the tool showing it in its normal closed position and illustrating the manner of initially engaging it with a piston ring.

Fig. 2, is a plan view showing the tool in an open position and illustrating the manner of expanding a piston ring.

Fig. 3, is a view in elevation of the jaw end of the tool showing the jaws in their closed position.

Fig. 4, is a view in elevation of the jaw

end of the tool showing the jaws in their open position.

Fig. 5, is an edge view of the tool.

Fig. 6, is an edge view of one of the jaws showing the jaw as adjusted for engagement with a wide piston ring.

Fig. 7, is a similar view showing the jaw as adjusted for engagement with a narrow piston ring.

Fig. 8, is a view in section and elevation of one of the jaw members as seen on the line 8—8 of Fig. 6.

Fig. 9, is a perspective view of a demountable spacing element for facilitating adjustment of the jaws for engaging piston rings, to be made in various sizes in accordance with standard widths of piston rings.

Fig. 10, is a view in section and elevation as seen on the line 10—10 of Fig. 1, illustrating the manner in which the tool is employed in engaging the split portion of a piston ring having stepped ends.

Fig. 11, is a similar view showing the manner in which the tool is engaged with the split portion of a piston ring having beveled or inclined ends.

Fig. 12, is a diagram illustrating the manner of initially inserting the jaws of the tool between the ends of a piston ring.

Referring more specifically to the drawings A and B designate opposed, blade-like jaws related for movements and held together as by a pivot-pin 15, and to which are connected handles 16 and 17 for their operation.

At their forward ends the jaws are reduced in their width dimensions, as at 18 and as shown best in Fig. 2, whereby to permit their introduction between the ends 19 and 20 of a piston ring which ring-ends are normally spaced by inherent ring expansion when released as upon withdrawal from a cylinder and as best shown in Fig. 12. At the extremities of the reduced jaw-ends there are the beaks, hooks, or ring-end engaging devices, 21. Along the lower inner margin of the jaw A and the upper inner margin of the jaw B are formed the vertical flanges 22 and 23, respectively, which constitute supports for piston-ring gripping and handling devices, as will be later described.

Each jaw A and B further comprises a stop 24 on the jaw A and a stop 25 on the jaw B, formed as marginal extensions, opposite to the

recited flanges 22 and 23, to check the closing movement of said jaws when they reach the position shown in Fig. 1.

The handles are sectionally shaped to provide ready and comfortable grasping by an operator, and each carries an ear 26 and each has formed therein a perforation 27.

The jaws and handles with the just described elements, are formed as units and 10 preferably as die-stampings and by still further preference of cold rolled sheet steel of approximately 16 gauge, and both jaws with their handles and the other recited parts are identical, to the end that a single stamped 15 piece will serve as either jaw A or B.

The piston-ring gripping and handling devices, referred to, each consists of a bearing 28 formed as a leaf and for extension laterally from and in planes above, or below, the 20 recited beaks, or ring-end engaging devices, 21, as best shown in Figs. 1 and 5, and has a base flange 29 for securement to a flange (22 or 23) of the jaws.

In order to provide for adjustment of the 25 bearing lengthwise relative to the jaw, I provide a bolt and slot connection as at 30, the slot by preference being formed in the flange of the jaw as shown.

Carried by each bearing 28 is a threaded 30 stem 31, on each of which is carried a pair of disc-shaped internally threaded elements 32 which constitute the referred-to piston-ring gripping and handling devices.

By reason of the threaded relation the ring 35 handling elements of each pair may be relatively adjustably spaced for adaptation to piston rings of different thicknesses, or vertical dimensions, and in order to provide for fixing the recited vertical spacing of the ring 40 handling elements whereby the tools may be "set" for repeated operations on a given size piston ring, I employ an adaptor 33, of open-seam sleeve shape which is mounted between each pair of ring gripping devices 32, about 45 the stems 31 and the gripping devices screwed tightly thereagainst. Means such as the simple integral stems, or tails, 34 are provided to aid in handling the adaptors. Threaded stem 31, the gripping elements 32, 50 and the adaptor 33 combine to form a ring holding device which is adapted to be locked in the adjusted position.

The means referred to for limiting the extent of opening the jaws A and B, comprises 55 the recited integral ears 26; 26 on the handles 16 and 17, one of which, is internally threaded and provides support for a screw 35 and the other of which, lying in the path of movement of the end of the screw serves as a stop. 60 Obviously by an adjustment of the screw the extent of jaw separation may be adjustably fixed for piston rings of varying diameters and characters.

To provide for more facile operation the 65 handles are normally held to open position

and to this end, I provide a spring 36 secured as by rivets in the referred to perforations 27 of the handles.

The adaptors 34, I contemplate furnishing in sets, of which each set consists of a 70 number of pieces of different height dimensions corresponding with different height dimension of piston rings to be operated upon.

The operation of removing a piston ring, 75 assuming the piston to be removed from a cylinder, consists in first moving the piston ring, manually, to eccentric position relative to the piston so that its spaced ends will be extended outside of the ring groove and beyond the outer face of the piston, as shown in Fig. 1. 80 The tool is then applied with its ring holding means, the discs 32, placed astride the ring and the ring spreading means, the beaks 21, inserted between the ends of the ring.

The handles 16 and 17 are then brought together, or toward each other, and the beaks 21 separated relatively whereby the ring ends are spaced and the ring, as a whole, diametrically increased to a dimension greater than the piston diameter whereby the ring may be 90 bodily removed from the piston.

The mounting of a ring is the same operation as the just described removing operation only in a reverse order.

I claim:

1. A tool of the class described comprising ring holding means consisting of relatively adjustable elements for adaptation to rings of different thickness, and adapted to be locked in the adjusted position, and means for spreading the ring ends and securing the spread ends in the ring holding means.

2. A tool of the class described comprising ring holding means, means for spreading the ring ends and securing them in the holding 105 means, means for relatively adjusting the holding and spreading means for adaptation to rings of different diametrical dimensions, and means for locking said holding means in the adjusted position.

3. A tool of the class described comprising ring holding means, means for spreading the ring ends, means for adjusting the tool for adaptation to rings of different diametrical dimensions, and means for adjusting the tool 115 for rings of different thickness.

4. A tool of the class described comprising ring holding means consisting of relatively adjustable elements spaced for straddling a ring, a removable and replaceable element 120 for determining the spacing of said ring holding elements, and pivotally related jaws for opposed movements against the ends of a ring.

5. A tool of the class described comprising 125 in combination a pair of jaws, pivotally related for opposed movements and having beaks at their free ends for insertion between and surrounding the ends of a piston ring, a threaded stem carried by each jaw, and a 130

pair of elements screwing onto said stem to engage opposite sides of a ring.

6. In a tool of the class described a unit, constructed of sheet metal and comprising a jaw, a ring end engaging device on the face of said jaw, a handle, a stop element for a handle motion limiting means, a support for a ring holding device, and a ring holding device on said support adapted to engage opposite sides of a ring.

7. A tool of the class described comprising

in combination a pair of jaws pivotally connected for opposed movement and having teeth at their free end for insertion between and surrounding the ends of a piston ring, ¹⁵ oppositely projecting marginal flanges on each of said jaws, and means adjustably supported on said flanges for engagement with opposite sides of a ring.

In testimony whereof, I have affixed by signature.

FRANK MILLER.
